(57) CLAIM

The ornamental design for a flag pole holder with base, as shown and described.

DESCRIPTION

FIG. 1 is a front side perspective view of a flag pole holder with base showing my new design;

FIG. 2 is a front elevational view thereof;

FIG. 3 is a rear perspective view thereof;

FIG. 4 is a rear elevational view thereof;

FIG. 5 is a top plan view thereof; and,

FIG. 6 is a bottom view thereof.

The broken line showing in the drawings is for illustrative purposes only and forms no part of the claims design.
